UNITED STATES PATENT OFFICE.

CHRIS N. SMITH, OF ELGIN, ILLINOIS, ASSIGNOR TO THE DAVID C. COOK PUBLISHING COMPANY, OF ELGIN, ILLINOIS.

METHOD OF PREPARING COLOR-PLATES FOR PRINTING.

SPECIFICATION forming part of Letters Patent No. 753,746, dated March 1, 1904.

Application filed January 10, 1903. Serial No. 138,542. (No specimens.)

To all whom it may concern:

Be it known that I, CHRIS N. SMITH, residing at Elgin, in the county of Kane and State of Illinois, have invented a new and Improved 50 5 Method of Preparing Color-Plates for Printing, of which the following is a specification.

My invention has for its purpose to provide an improved method of preparing relief- 55 plates for color - printing, whereby relief- 10 plates used in ordinary newspaper or book printing can be expeditiously prepared for printing the desired colors in a manner requiring much less work and effecting a great saving in expense when compared with the 15 present methods employed for color-printing and by which the plate can be wholly prepared without the aid of skilled labor and the engraving and etching done by hand by experienced engravers, required in the present 20 methods of preparing color-plates, is entirely dispensed with.

As is well known, in the methods now commonly employed for preparing color-plates for letter-press printing it is usual to transfer 25 all colors on a separate plate, which is then engraved and etched before it may be ready for electrotyping.

My improved method in its generic nature differs from the methods now generally employed in that no etching or engraving of the 30 plate is required and in that the treatment of the plate is such that it is made possible and perfectly practical to make from one to four colors by my process.

With the above and other objects in mind my invention consists in the method of preparing a relief-plate for color-printing, hereinafter fully described, and specifically pointed out in the appended claims.

In order that my invention may be better understood, attention is directed to the accompanying drawings, in which—

Figure 1 shows a portion of an original relief-plate for letter-press printing which may be in the nature of an electrotype, stereotype, or an ordinary type-form. Fig. 2 is a representation of the plate shown in Fig. 1 after receiving the first step of my method—that of

applying the composition for filling the face of the plate at the places where it is intended to make the color impressions. Fig. 3 shows the said plate after it has received the second step of my method—that of cleaning away the filling at the desired points. Fig. 4 illustrates a slight modification of my method; and Fig. 5 is a section of a portion of a plate constructed in accordance with my invention with the filled surfaces a' , hereinafter referred to, in a plane parallel with but slightly higher than the remaining surfaces of the plate. Fig. 5^a is a section of a portion of a plate, illustrating a part of the filling cut away for the purposes hereinafter explained.

The original plate, either an electrotype, a stereotype, or an ordinary type-form, is filled at the points where it is desired to have the imprints in colors with wax or any other composition that will stand the heat like wax. This filling (indicated by a) is then smoothed down in a parallel plane with the printing-surface of the plate and is preferably built up a little higher than the said surface, as diagrammatically indicated by a in Fig. 5. When the plates are half-tones or solid, the filling a has its surface a' burnished smooth, as shown, at the parts 1 1^a, whereby to present a solid ink-taking surface; but where the cuts or designs are open the wax from that part thereof not intended to appear in color is cut away down to the metal surface 1, as indicated by 2 in Figs. 3 and 5^a.

So far as described it will be readily apparent that by reason of having to remove the soft filling rather than the hard metal a great advantage is obtained over the old method, in which the cutting away of the metal is necessary to eliminate from the plate the impression-surface not to appear colored in the print, it being obvious, however, that in the event of the built-up portion or filling a being shallow—that is, its outer or impression surface being substantially flush with the metal impression-surface of the plate—the metal at the blank or open spaces from which the wax filling is to be removed may also be cut away to have the desired results, as shown in Fig. 4.

When the cuts of the plates are solid—that is, when it is desired to print a solid color entirely over the cut or illustration indicated by 5 in Fig. 1—the wax filling is smoothed off solid with the printing-surface of the cut, so as to completely fill all of the “white” spaces or stippled indentations when the cut is a half-tone, and the said surface is burnished whereby to produce, as it were, a solid smooth printing-block, as indicated by 5 in Fig. 3.

Another important advantage incident to my method is that by pressing a screen on the wax or composition filled in on the original plate the color-printing surfaces may be stippled or screened fine or coarse, as desired, and exactly the same results obtained thereby as would be the case were the old method employed—that is, stippling or screening the said color-printing surfaces by the aid of an engraving-tool or etching—and the said result is obtained without the aid of skilled labor, as the skill of an engraver or etcher is thereby entirely dispensed with. One of the screens or stippled surfaces is indicated by 5^x in Fig. 3.

25 After the original plate is treated in the manner before described a copper shell thereof is formed by electrotyping in the usual way, since the composition or filling *a* hardens when it sets, so as to permit of electrotyping. 30 The electrototype-shell is then backed up and finished, as would be the case with an ordinary electrototype-plate, the difference between the old method and my method of producing color-plates being wholly in the preparation of 35 the plate for the color-work.

Since in the present method of preparing color-plates it is necessary to transfer all colors on a separate plate, which plate is then engraved or etched before being ready for 40 electrotyping, it follows that as the said requirements are not necessary in my method a great saving of time is effected in making the form ready for color-printing, for the reason that in my method the work of removing those 45 portions of the plate not to appear in color on the print is done in wax or other composition and easily scraped away from the hard metal.

The expense of preparing the plate is by my method greatly reduced, as in the practical application of the same I have found it possible 50 to turn out twelve plates by my method in the time required to turn out one plate by the old method.

Having thus described my invention, what

I claim, and desire to secure by Letters Patent, is—

1. The method of preparing an original relief-plate for the purposes described which embodies the following steps: first, applying a filling of wax or other similar composition 60 to the surface of the said original relief-plate, smoothing the said filling in the plane parallel with the said surface; second, removing the said filling from those parts of the original relief-plate not to appear in color on the print 65 which may be made from the plate, as set forth.

2. A method of preparing an original relief-plate for the purposes described, which consists in, first, applying a layer of yielding plastic material, capable of resisting heat, and 70 smoothing said material in a parallel plane with and slightly above the printing-surface, and second, removing the said material from those parts of the plate which are not to appear in color, upon the print which may be made 75 from the finished plate, as specified.

3. A method of preparing an original relief-plate for the purposes described, which consists in, first, applying a filling of plastic material capable of resisting heat on the printing-surface of the said original plate, and 80 smoothing and burnishing said filling in a plane parallel with the said surface, as hereinbefore described.

4. The method of preparing an original relief-plate for color-printing which consists, first, in applying a filling of wax or similar composition to the surface of the said original plate, second, smoothing the said filling in a plane parallel with the said surface, and third, 85 indenting the said composition surface by a screen or similar means, for the purposes stated.

5. An original relief-plate having a plastic filling on the impression-surface thereof which 90 covers all that portion of the plate to be utilized as a color-printing surface, as set forth.

6. A relief-plate of the character described, having a plastic filling on a portion of the impression-surface whose printing-face is in 100 a plane parallel with and slightly above the remaining portion of the impression-surface of the relief-plate that is free of the filling, as set forth.

CHRIS N. SMITH.
